UNITED STATES PATENT OFFICE.

GEORGE H. ELLIS AND JOHN F. STEWARD, OF CHICAGO, ILLINOIS.

GEAR FOR MOTOCYCLES.

SPECIFICATION forming part of Letters Patent No. 570,203, dated October 27, 1896.

Application filed January 23, 1896. Serial No. 576,543. (No model.)

To all whom it may concern:

Be it known that we, GEORGE H. ELLIS and JOHN F. STEWARD, of Chicago, in the county of Cook and State of Illinois, have invented 5 certain new and useful Improvements in Gears for Motocycles, of which the following is a full description, reference being had to the accompanying drawings, in which—

Figure 1 is a plan view of a carriage, showing our invention. Fig. 2 is a side elevation of the same, and Figs. 3, 4, 5, 6, 7, 8, 9, and 10 are details of construction.

The object of our invention is to provide connecting-gearing between the engine or other source of power and the traction-wheels, whereby the speed of rotation of the engine or other motive power is reduced in its transmission and the power imparted to the traction-wheels, and also provide convenient 20 means for controlling the rate of speed of the carriage propulsion and, as well, its direction of travel.

A and A are the traction-wheels of the engine, and A' and A' the steering-wheels. These 25 are secured to axles in the ordinary manner, the frame-bars of the carriage B and B' being secured directly to the axle C at the rear and at front of the carriage to a bar D, that rests upon the axle E. This bar and the axle are 30 pivoted together by the king-bolt e. Upon the front axle is secured a segment e', and adapted to move this is a pinion e''. So far the carriage need not differ from those now in common use.

F may be considered as a gasolene-engine, a gas-engine, a steam-engine, or in fact a 35 motor. For our present purposes it is only necessary that it have the shaft F', adapted to be revolved at any suitable speed.

Suitably supported on the bars B and B' 40 are the bearings b and b'.

b² is a shaft that we prefer to extend all the way across the carriage-frame, as may be seen in Fig. 1. It is provided with a sprocket-wheel b³ at its left end, as seen in Fig. 1, and 45 adjacent to the engine is secured the bevel-gear b⁴.

b⁵ is a sleeve, into and preferably through which the shaft b² extends. At its inner end, 50 adjacent to the wheel b⁴, is the bevel-gear b⁶, and upon the outer or right end of the same is the sprocket-wheel b⁷. The purpose of ex-

tending the shaft b² through the sleeve-like shaft b⁵ is to enable us to support both parts in two simple bearings.

The two bevel-gears referred to form parts of a differential driving-gear. (Shown in section in Figs. 7 and 8.) Between the two bevel-gears is placed the sprocket-wheel G, and within recesses of the sprocket-wheel are 60 placed the bevel-pinions g. This sprocket-wheel is adapted to move freely on the shaft, but the pinions engage the bevel-gears, between which they are, and which are secured each to one shaft. This differential gearing 65 is used for the purpose of allowing each of the traction-wheels to revolve independently when the carriage is traveling on an arc of a circle, as in turning corners, and, not differing from that used on various traction-engines, need not be further described. It will 70 form, however, an element of some of our combination claims.

Our mechanism for controlling the rate of travel and direction of movement, either forward or backward, may be more easily understood by reference to Fig. 7, where the shaft F' is shown, with all the parts which it controls, in section. Upon this shaft is supported a disk H, having a suitably-grooved hub h. In this 80 disk the shaft F' is free to turn, except when the operator is permitted to so move it longitudinally upon the shaft that it will be, in effect, locked to the shaft through instrumentalities to be explained, so that it is forced to 85 turn with the shaft at the same rate of speed as the latter, or at a less rate of speed, at will. Supported upon this shaft by a bearing formed therein and to the framework of the carriage through the bolt-holes j is the support J, to which, at i, the lever I is pivoted. This support we prefer to so adapt as to serve 90 as a housing for the gearing it is shown to inclose as well as a stationary brake to effect the action of the disk H and the gears it carries. Upon the pins h' we support the pinions h², 95 adapted to mesh into the pinion f.

Loosely upon the shaft F' is placed the internal gear K, having its teeth adapted to also engage the pinions h². A side elevation 100 of the various gears is shown in Fig. 6. The internal gear K is free to turn on the shaft F', but is held from longitudinal movement between the pinion f and the collar f' and is se-

cured to the shaft F. To the hub of this gear K is secured the sprocket-wheel F². It may be formed as one piece with the internal gear-hub, or in any other manner positively secured thereto. The disk H has the flange h³, and to this flange are secured, by rivets, cushions of leather h⁴.

The housing J is smoothed at its interior surface adjacent to the position of the flange h³, and its cushions, of leather or other suitable material, and the outer periphery of the web of the internal gear K, are also turned or otherwise made smooth.

It will be observed that the inner surface 15 of the housing J at the point adjacent to the leather or other braking-surfaces forms the frustum of a hollow cone, and that the outer surface of the web of the internal gear K forms the outer surface of the frustum of a 20 cone.

Upon the arm I are placed antifriction-rollers (shown in dotted lines in Fig. 3) that enter the groove in the hub h of the disk H. By movement of this lever, then, the disk H 25 is moved longitudinally upon the shaft F'. It will be seen that in Fig. 3 it is shown as moved to the right, and that the brake-pad h⁴ is made to contact with the outer periphery of the internal gear K, and that the brake- 30 surface is not in contact with the housing J. It may be said, in passing, in order to make the matter clear, that the disk H serves, among other purposes, that of the movable part of a 35 brake that is adapted to prevent itself from turning by being forced against the stationary housing, or at other times to compel the gear K to move when it is itself moved. If attention be directed to Fig. 4, it will be seen that the brake-surfaces are shown close in contact 40 with the housing. With the parts in this position the disk H will be restrained from rotating. In Fig. 3 the braking-surface is shown as forced into contact with the gear K, so that if the disk were given rotation it 45 would also compel the internal gear K to rotate.

In Fig. 5 the brake-surfaces of the disk H are shown not to be in contact with either the stationary housing or the gear K.

50 The operation of our driving-gearing is as follows: The shaft F' may be supposed to be a continuously-running shaft, always in one direction, and the housing J, which is, in fact, a stationary brake, fixed to the gearing-carriage, the engine-bed, or other suitable place. The pinion f being rigidly secured to the shaft F is thus adapted to rotate continuously. Let us now suppose the lever I to be in the 55 position shown by dotted lines in Fig. 3, that is, with the disk H so forcibly drawn against the stationary brake J that it (the disk) cannot rotate. The pinion f will turn the pinions h² on their supporting-studs in a direction opposite from that of the shaft F, and as 60 they mesh into the internal gear formed in the disk K the said disk will be driven in a direction opposite to that of rotation of the

shaft F, and the sprocket-wheel F², secured to the disk, will be moved in the same direction. This sprocket-wheel F² is provided 70 with a chain that passes around the sprocket-wheel G of the differential gearing first described. Let us now assume that the shaft of the engine or other suitable motor is moved in the direction indicated by the arrow on the 75 balance-wheel secured to the said shaft. With the parts in the position just mentioned, and the result being a rotation of the sprocket-wheel F² in a direction reverse to that of the shaft F, the movement imparted to the traction-wheels through the instrumentality of the differential gearing and the connecting-chains will be such as to back the carriage. As the pinion f is small and the gears h² upon 80 axes that are for the time being considered 85 fixed, the latter serve but as intermediates to transfer motion from the said pinion f to the internal gear K, which is much larger than the said driving-pinion f, and the result is that the said gear is revolved not only in a 90 reverse direction, but at a much slower rotation than the shaft of the engine.

We have shown sixteen teeth in the pinion f and forty-eight in the internal gear K, the result of which is that the gear K, and hence 95 the sprocket-wheel F², secured to it, will move at only one-third of the rate of speed that the gear moves. The motive force being constant it will be clearly understood that the reduction in speed would result in an increase of 100 the power applied to the sprocket-wheel F², the result of which is, in turn, that the carriage moving backward would move slowly, but with great power. It is never necessary to run a carriage at a high rate of speed backward, and hence we make the gear f small in 105 proportion to the internal gear K. To do this, it is only necessary for us to make our intermediate gears h² of suitable size to intermesh with the gears referred to. The advantage we gain is this: We are enabled to gear our carriage so that when going forward a 110 good rate of speed may be attained. If, however, a person running our carriage gets into miry places or ruts that stall him, he can reverse the movement and back out. Having 115 at his command a force at least three times as great as that which carried him in, he can back out of any difficulty. If now the operator wishes to run the carriage forward, 120 he shifts the lever I to the position shown in full line in Fig. 3, in which case it will be observed that the braking-surfaces of the flanged disk H and the gear K are brought in contact. As the angle of the braking-surfaces 125 relative to the axes of the said disks is very small, but little pressure upon the lever I is required to hold disks H and K so firmly together as to practically be as one piece. Let it be observed that the pinions h² are supported on the disk H and if they cannot turn on their axes they practically lock the disk H 130 to the pinion, and as the latter rotates the disk H is forced to rotate. With now the

said disk H locked by the friction of the brake-pads to the disk K it is also forced to rotate and carry with it the sprocket-wheel F². The two disks, the gears between them, and the 5 pinion upon the shaft being practically all locked together, the sprocket-wheel F², secured to the disk K, is forced to rotate in the same direction as the shaft F and at exactly the same rate of speed. By this last adjustment 10 of the lever I it is seen then that the sprocket-wheel F² is adapted to move the carriage in a forward direction at a high rate of speed. These two directions of speed, it has been shown, are controlled by the lever I, first, 15 by forcing it in one direction and then in the other; but let us now suppose that the said lever be placed in a medium position, so that the brake-surfaces of the disk H will neither come in contact with the stationary brake formed in this instance by the housing nor 20 with the periphery of the disk of the internal gear K; and let it also be supposed that the carriage is standing upon the ground so that there is some little resistance to movement. 25 The result will be that as the rotation of the disk K is thus resisted the pinion f, through the instrumentality of the intermediate orbitally-moving gears h², rotates the disk H, as there will be no braking resistance to hinder, the result being that H will rotate idly, 30 for, as stated, its rotation is not resisted by the stationary brake, nor is its motion imparted to the disk K, for it does not come in contact therewith. Let us now suppose the carriage to be standing and the lever I be moved nearly to its position shown in Fig. 3. The brake-surface of the disk H will be forced 35 against the surface upon the disk K, with which it co-operates, and the carriage will be started forward, but as we have not yet moved the lever I to its farthest extent the frictional contact of the brake to the periphery of the disk K is not great and the carriage will be moved forward with but little 40 force, and consequently will move only at a slow rate of speed. If it is desired to increase the speed, then the lever will be moved a little farther to the right, so as to produce greater frictional contact within the driving and the 45 driven surface, when the speed of the carriage will be increased. In this instance, with the shaft F rotating at its full rate of speed, the speed of the engine will be divided and a portion of it go to waste through such idle 50 movement of the disk H. The action can be well illustrated by comparing it with ordinary friction-gearing, where the frictional contact is made variable at will, as used in various kinds of machinery. If it be desired 55 to move the carriage backward very slowly, it is then only necessary to force the lever I to the left less than the full distance, when the disk H will be only a little resisted from 60 rotating and a part of the movement of the shaft F' be idle. We have, it will now be understood, a compact nest of gearing upon 65 a single shaft adapted to impart motion from

that shaft to mechanism that it is desired to drive in either direction required at any rate of speed desired, or to stop the movement, 70 and all of these at will and through the instrumentality of a single lever. It is also seen that the same has all the functions of friction-gearing, so that all movements may be controlled in the gentlest possible manner 75 and all shocks be avoided. The method chosen for operating the controlling-lever I is shown in Figs. 1, 2, and 9.

l is a hollow shaft supported in a bearing l' upon the flooring of the carriage-body and a bearing l², supported by the brace l³ and extending to any suitable position, as, for instance, the flooring of the carriage. This hollow shaft is adapted to revolve freely and carries with it the eccentric M, which we groove from preference, and spans the brace m and m' of the lever I. Upon these spanning portions we provide pins that enter the slot in the eccentric M. These grooves and pins are for the purpose of sustaining the end 85 of the lever in proper relation to the eccentric. Upon the upper end of this hollow shaft is a hand-wheel M', which may be considered as a lever or any suitable means by which the hollow shaft is rotated. If, now, the hand-wheel be rotated in one direction, the eccentric is carried to the position shown in Fig. 1, where the lever I is so moved as to cause the carriage to move ahead. If, however, the said hand-wheel be given a half-rotation farther 90 or a half-rotation backward, the eccentric will be moved so as to carry the lever I to its other extreme, and the gearing thus adapted to move the carriage backward. If, however, the hand-wheel be turned so that the eccentric shall be in a middle position, the braking-surfaces of the disk H will be out of contact with anything and the carriage stand 95 idle. Our purpose in making the shaft hollow is to make it also support the shaft N, to 100 which the steering-pinion e² is secured at its lower end. Upon the shaft at its upper end is a hand-wheel n. While traveling, the operator must have his hands upon the hand-wheel n or other suitable means for controlling the latter, but it is not necessary that he manipulate the wheel n only at such time as he wishes to move cautiously. There is no 105 tendency for the parts to move, but with the eccentric only partly turned they might be moved by the jarring of the carriage. To prevent this, we apply a ratchet-wheel l⁴ and the spring-pawl l⁵, adapted to co-operate therewith, the teeth of each being so made that a little force will move the ratchet-wheel. This 110 construction is shown in Figs. 2 and 10.

It will be observed that in our reversing device we have two disks moving freely upon a shaft and means for locking them together, and when we speak of means for doing this in the claims we mean the manner shown or its equivalent, and wherever the term "means for" is used in the claims we mean that the joint action of certain of the elements, per-

forming a function, as they do, may be considered as one element of the claims.

As the results reached by our reversing arrangement are due to the relative movement of the disks H and K it is evident that means can be employed for moving the disk K longitudinally on its axis relative to the disk H, but of course in such a case a modification of the braking devices would be required.

10 We are aware that mechanisms have been located upon a shaft in such a manner as to give motion to machinery and drive it in either direction at will, and we do not claim to be the first to accomplish such a result, 15 broadly considered; but

What we do claim is—

1. The continuously-running pinion f , the disks H and K supported concentrically relative to the said pinion, the said disk K forming an internal gear, and the said disk H having, upon suitable supports, the gear or gears h^2 adapted to mesh into the said pinion f and into the internal gear of the disk K, the friction-ring J, and means for clutching the disk H to the said ring or to the said disk K, at will, substantially as described.

2. The continuously-running pinion f , the disks H and K, supported concentrically relative to the said pinion, the said disk K forming an internal gear, and the said disk H having, upon suitable supports, the gear or gears h^2 adapted to mesh into the said pinion f and into the internal gear of the disk K, means for moving the said disk H laterally whereby it may be either held from rotation, may be clutched to the disk K or may be set free and thus set free the said disk K, at will, substantially as described.

3. The continuously-running pinion f , the disks H and K supported concentrically relative to the said pinion, the said disk K forming an internal gear, and the said disk H having, upon suitable supports, the gear or gears h^2 adapted to mesh into the said pinion f and into the internal gear of the disk K, a wheel secured to the said disk K, the friction-ring for imparting motion to the machine to be actuated, and means for moving the disk H laterally whereby it may be held from rotation or may be held to the disk K or may be set free from both at will, substantially as described.

4. The continuously-driven pinion f , the disk H, having an annular friction-flange and adapted to move laterally, a planet gear or gears suitably supported on said disk, the internal gear adapted to be held from lateral movement and having an annular friction-flange inside that of the disk H, a stationary friction-ring outside of the said disk H and means for moving the said disk H laterally whereby it may frictionally clutch the said friction-ring or the said internal gear, or may be held free from both at will, substantially as described. 65

5. In a motor cycle and in combination, a motor having a driving-shaft, a driven wheel mounted loosely upon and concentrically with the driving-shaft, a pinion on said shaft, planetary gearing supported upon said driving-shaft and having a disk adapted to move laterally, the said planetary gearing constructed substantially as described, whereby the said driven wheel is rotated in either direction, means within reach of the operator 75 for moving said disk, counter-shafts mounted on coincident axes, each shaft being suitably connected to the driving-wheels of the motor cycle and differential gearing mounted upon the adjacent ends of said counter-shafts and 80 rotated by said driven wheel, substantially as described.

6. In a carriage a motor having a continuously-driven shaft, an internal gear K loosely supported on the shaft thereof, a pinion f 85 keyed to the said shaft, the disk H loosely mounted on the said shaft and adapted to be moved in longitudinal directions, the intermediate gears upon the said disk H adapted to engage the pinion f and the intermediate 90 gears of the disk K, a power-transmitting wheel as one piece with the said disk K, gearing adapted to transmit motion from the said power-transmitting wheel on the said disk K to the traction-wheels, and means under the 95 control of the attendant for moving the said disk H longitudinally, substantially as described.
